UNITED STATES PATENT OFFICE.

VIRGIL V. LOOMIS, OF PITTSBURGH, PENNSYLVANIA, ASSIGNOR TO UNITED GLASS COMPANY, OF PITTSBURGH, PENNSYLVANIA, A CORPORATION OF PENNSYLVANIA.

DESIGN FOR A GOBLET.

Application filed September 28, 1926. Serial No. 19,189. Term of patent 14 years.

To all whom it may concern:

Be it known that I, VIRGIL V. LOOMIS, a citizen of the United States, residing at Pittsburgh, Allegheny County, Pennsylvania, have invented a new, original, and ornamental Design for a Goblet, of which the following is a specification, reference being had to the accompanying drawing, forming part thereof.

The figure is a perspective view of a goblet showing my new design.

While the drawing shows a complete goblet, the dominant feature of the design is the particular form of stem between the foot and bead.

I claim:

The ornamental design for a goblet, substantially as shown and described.

In testimony whereof I have hereunto set my hand.

VIRGIL V. LOOMIS.
